UNITED STATES PATENT OFFICE

2,338,161

METHOD OF MANUFACTURING SHEAVE WHEELS

William A. Ashton, Pittsburgh, Pa., assignor to Carnegie-Illinois Steel Corporation, a corporation of New Jersey

Application March 28, 1942, Serial No. 436,688

3 Claims. (Cl. 80—60)

The present invention relates to an improved method for rapid manufacture of sheave wheels.

An object of the invention is to simplify the method of manufacturing peripherally grooved sheave wheels and at the same time to improve the metal by subjecting the fibers of the peripheral grooved portion to a rolling operation in order to bring about plastic flow and render the metal in the critical peripheral zone of the sheave wheel more dense and homogeneous than that of a cast wheel or of a wheel formed by simple pressing or forging operations.

As will be more fully pointed out hereinafter, the present invention contemplates starting with a rough wheel blank of approximately cylindrical form which is subjected to a plurality of rough forging operations so as to transform the cylindrical blank to an intermediate blank consisting of relatively thick hub and rim portions connected by a thinner web portion. This latter blank is subjected to a rolling operation in such a way that the outer annular region of the rim is confined so as to prevent lateral plastic flow or movement of the metal beyond predetermined limits, while at the same time exerting rolling pressures on opposite faces of the web and the inner annular faces of the rim, the blank being supported in a manner to permit rotation about an axis centered within the rim, and during the aforesaid steps forcing an annular median peripheral portion of the rim inwardly to form the sheave groove while rotating the blank on its axis, whereby the metal structure, particularly in the rim region and outer peripheral region of the web, is rendered very dense, tough, and homogeneous because of such roll-forging operations.

For a more complete and detailed disclosure, reference should be made to the following detailed specification, the accompanying drawings and the appended claims.

In the drawings:

Figure 1 is a sectional elevation through suitable apparatus used in practicing the method of the present invention;

Figure 2 is a view of the starting blank from which the wheel is made; and

Figures 3, 4 and 5 are cross sectional views illustrative of the condition of the blank and finished sheave wheel at different stages in the method.

Referring to the drawings, in carrying out the method I first provide a substantially cylindrical blank 10 of steel, wrought iron or the like, such as shown in Figure 2. This blank is subjected to forging operations in a somewhat conventional

manner by the use of known types of dies and drop forging hammers so as to produce the blank of substantially the configuration indicated at 12 in Figure 3.

5 The forged blank 12 is then subjected to a further forging operation so as to transform it into the cross sectional size and shape shown in Figure 4, where it is seen that the blank consists of a relatively thick central hub portion 14 and 10 a similar thick annular rim portion 16, the hub and rim portions being connected by an intermediate relatively thinner web portion 18. Under the present invention, a blank such as shown in Figure 4 is subjected to a special type of rolling 15 treatment constituting an essential feature of novelty of the method claimed herein. This treatment is such that the wheel blank is rotated on its axis while the outer region of the web, the outer periphery of the rim portion and the side faces of the rim portion are all simultaneously subjected to rolling pressures and while this rolling is being accomplished, a median portion of the face of the rim is being forced inwardly so as to form an annular groove and also densify 20 the metal in the outer annular region of the sheave body.

To these ends the wheel blank is provided with an axial opening, indicated at 20 in Figure 1, for engagement with an arbor or spindle 22 which 30 is effective to support the blank with freedom to rotate about the axis 24. While the blank is rotated on its axis, the web thereof is subjected to rolling pressure exerted by the opposed double-coned rolls 26 and 28 carried by rotating spindles 30 and 32 mounted in suitable bearings 34 and 36. The rolls 26 and 28 are mounted on the extremities of respective roll necks 38 and 40, the outer ends of which are flanged and connected to conventional power driven rolling mill elements 42 and 44.

40 The specific rolling mill structure employed forms no part of the present invention and may be of conventional form, such as that frequently used in the roll-forging of car wheels. Means such as indicated at 46 and 48 are provided with swivel joints for pressing the rolls 26 and 28 firmly against the blank being rolled.

It is a characteristic feature of the present invention to confine the annular rim portion of the blank during the rolling operation, and while the rim is so confined, to subject the annular body of rim metal to an inward rolling pressure which is counteracted by the rolling pressure exerted by the rolls 26 and 28. To secure this desirable action I utilize a backing roll 50 formed

with an annular groove 52 flanked by side flanges 54 and 56 which serve to confine the outer faces of the wheel blank to thus prevent plastic flow or lateral movement of the rim metal beyond predetermined limits. The critical limits may be precalculated to suit the size of the particular sheave wheel rim to be formed. While the rim metal of the wheel blank is thus confined, between the side flanges 54 and 56, it is also being subjected to an inward rolling pressure exerted jointly by an annular bead 58 formed on the backing roll 50 and the annular bearing faces 60 and 62 of the backing roll 50.

The backing member 50 is rotatably mounted on a center bearing 64, which is adjustably supported in arms 66 and 68 of a yoke-like member which includes a thrust rod 70 connected with power driven means effective to force the backing member 50 toward the wheel blank under treatment. In the normal operation of the method it will be understood that the wheel blank such as shown in Figure 4 will, when subjected to the rolling pressures described, be transformed into the cross sectional shape shown in Figure 5. During this transformation, conjoint action of the rolls 26 and 28 and the backing up roll 50 simultaneously exerts rolling pressures on opposite faces of the web and inner annular face of the rim while at the same time the annular bead 58 forces the peripheral annular median portion of the rim body inwardly against the rolling forces exerted on the web and rim. These combined forces thus subject the fibers of the rim and the outer portion of the web to a vigorous rolling compression which is effective to bring about a plastic flow and to toughen or densify the peripheral rim of the wheel.

While I have described quite precisely the specific steps which a reduction to practice has shown to be desirable and have illustrated a specific type of wheel rolling mill apparatus of preferred design, it is not to be construed that I am limited thereto since various modifications

and substitutions of equivalents may be made by those skilled in the art without departure from the invention as defined in the appended claims.

I claim:

5. In the manufacture of sheave wheels, the method which comprises forming a blank consisting of relatively thick hub and rim portions connected by a thinner web portion, and simultaneously subjecting opposite sides of both the web and rim portions to rolling pressure while at the same time forcing an annular median portion of the rim body inwardly with a rolling pressure, thus forming an annular groove in the blank and working the fibers of the rim body inwardly.
10. 2. In the manufacture of sheave wheels, the method which comprises forming a blank consisting of relatively thick hub and rim portions connected by a thinner web portion, exerting rolling pressures on opposite faces of the web and on the inner annular faces of the rim while simultaneously forcing the peripheral annular median portion of the rim body inwardly against the said rolling forces exerted on the web and rim to thus form an annular groove and subject the fibers of the rim and outer portion of the web to a vigorous rolling inwardly directed compression to thereby toughen the peripheral grooved portion of the sheave wheel being formed.
15. 3. In the manufacture of sheave wheels, the method which comprises forming a blank consisting of relatively thick hub and rim portions connected by a thinner web portion, confining the outer annular region of the rim against plastic flow or lateral movement beyond predetermined limits, exerting rolling pressures on opposite faces of the web and the inner annular faces of the rim, supporting the blank in a manner to permit rotation about an axis centered with the rim, and forcing the annular central peripheral portion of the face of the rim inwardly while the blank is rotating on said axis and while the said outer region is confined as before mentioned.

WILLIAM A. ASHTON.
